UNITED STATES PATENT OFFICE.

EDWIN E. SLICK, OF WESTMONT BOROUGH, PENNSYLVANIA.

RAIL-JOINT.

1,078,220.

Specification of Letters Patent. Patented Nov. 11, 1913.

Application filed March 13, 1913. Serial No. 753,921.

To all whom it may concern:
Be it known that I, EDWIN E. SLICK, a citizen of the United States, residing in the borough of Westmont, in the county 5 of Cambria and State of Pennsylvania, have invented certain new and useful Improvements in Rail-Joints; and I do hereby declare the following to be a full, clear, and exact description of the invention, such as 10 will enable others skilled in the art to which it appertains to make and use the same.

My invention consists generally of an improved joint for the abutting ends of railroad rails which is well adapted to maintain 15 the rails in alined position, both vertically and laterally, and to provide a junction which is uninterrupted of substantially the same strength and elasticity as the body or intermediate portion of said rail, all of 20 which conduces to a smooth or easy-riding track.

Although my joint is adapted to, and may be used with, rails of different forms and sections, I will, for the purpose of simplifying the present description, confine the 25 specification and drawings to its use in connection with T-rails.

In my improved rail joint, the outer sides 30 of the heads of the ends of the abutting rails are cut away for a short distance, the direction of the cut immediately adjoining the rail ends, being preferably substantially parallel to and a prolongation of the outer surface of the rail web, the width of the cut 35 in each rail head merging or diminishing laterally, gradually in a concave curved form until its surface intersects the outer lateral surface of the rail head.

By the outer surfaces of the rail head, I 40 mean those on the outside of the track, as distinguished from the inner surfaces of the rail head, which are on the inside or what is known as the gage side of the track. The outer surfaces of the head of the rail 45 are, therefore, that portion which does not contact with the flanges of the wheels, or the portion of the wheel tread adjacent to the flanges of the wheels which pass over the same; whereas the inside or gage side of 50 the rail head is that which contacts with said portions and guides the wheels by means of their flanges. This cut in the rail heads, previously mentioned, may readily be made by means of a milling cutter of cylindrical outline, the axis of which is substantially parallel to a line passing vertically

through the center of the rail web, and this cut in the rail head is preferably made by beginning at the end of the rail and traversing it in a direction parallel to its axis, the 60 finishing curve being formed by the circumferential shape and the movement of said cutter. I may, however, make the cut in the rail head in any other manner or form, by planing, slotting, forging or otherwise, as 65 may be found expedient or necessary.

On the outer side of the rail I provide a splice bar of peculiar conformation, the extending end portions of the preferred form of which are adapted to fit in what are 70 known as the fishing angles, that is, underneath the rail head and on top of the rail base flanges, and I provide a clearance or distance between said outer splice bar and the rail web to allow it to be drawn up and 75 tightened and thereby make a rigid joint, and also thus provide for wear of the contact surfaces. The central or intermediate part of my splice bar is provided with an upwardly extending portion which is 80 adapted to fit within the cuts formed in the outer sides of the rail heads, as previously mentioned, the form of this upwardly projecting portion being such that the cross section of the rail head is restored by this 85 projection, so that at the joint the shape and form of the rail head are substantially the same as that of the head of an uncut rail.

On the inner or gage side of the joint I 90 provide an angle bar which may be of the usual shape of such constructions, and my splice bars may be held in place by bolts as usual, or otherwise, as desired.

My improved rail joint is so designed 95 that the section of the rail tread at the joint is substantially as elsewhere, while the central portion of the outer splice bar provides a bridge which enables the car wheels to pass over the joint or space between the abutting ends of the rail without jar, and the entire joint is so proportioned 100 as to have, as near as may be, the same strength and elasticity as the unbroken rail, thereby causing no undue deflection or jar 105 at the joint, which is a desideratum.

In order that the rail head portion of my outer splice bar may best serve its purpose, I prefer to form said splice bar of hard and tough steel material due to high carbon 110 content or otherwise, or of approximately the same composition and physical qualities

as the rail head itself, or, I may even make it somewhat harder, tougher and more elastic by heat treatment, that is, by heating the bars to the required temperature, 5 quenching and annealing them in oil or other media.

Having thus given this general description of my invention, I will now, in order to make the matter more clear, refer to the 10 annexed two sheets of drawings which form part of this specification and in which like characters of reference indicate like parts:—

Figure 1 is a top plan view showing the abutting ends of two T-rails, each cut out 15 on the outer side of the head, also showing the head portion of my outer splice bar fitting within said cuts. Fig. 2 is an outside elevation corresponding to Fig. 1 showing my outer splice bar in connection with the 20 abutting ends of the rails. Fig. 3 is an end elevation of my improved outer splice bar showing in dotted lines the shape of one style of the upper portion of the rolled bar before it is cut, formed and finished into 25 the shape shown in Figs. 1 and 2. Fig. 4 is a vertical transverse sectional elevation taken on the line IV—IV of Fig. 2. Fig. 5 is a vertical transverse section of one form 30 of a rolled bar of metal from which my improved splice bar may be made. Fig. 6 is a front elevation of my improved outer splice bar showing the portions to be sheared from the upper flange in curved cuts as indicated by the dotted lines. Fig. 7 is a top 35 plan view of my improved outer splice bar showing similarly by dotted lines, the portions to be sheared or cut therefrom to produce the finished form. Fig. 8 is a top plan view of my outer splice bar in one of its 40 completed forms. Fig. 9 is a perspective illustration of my improved outer splice bar looking at the inner portion thereof. Fig. 10 is a vertical transverse section 45 through the head of a rail and my improved outer splice bar taken on the line X—X of Fig. 1, this figure also showing in dotted lines the outline of a worn car wheel in position on the rail while passing over my improved joint. Fig. 11 is a plan view of my 50 improved outer splice bar, the central portion of which is shown as straight in plan to fit within the corresponding cuts in the rail head, while the outer portions of said splice bar are curved as indicated to allow 55 said curved portions to be drawn into position in the fishing angles of the rails, by means of the outer pairs of bolts, in order to make a particularly tight and secure joint, or to allow the same to be drawn up 60 from time to time to provide for wear of the contact surfaces. Those portions of the splice bar illustrated in Fig. 11 which fit under the rail head and on top of the base flange of the rail, should preferably be 65 formed in such shape that they will contact

with the same when the splice bar is first put in place, leaving the additional movement, when screwed up farther, to more firmly wedge the bar within the fishing angle of the rail.

70

Referring now to the various characters of reference on the drawings:—1 represents the end of a T-rail in place in the track; 2 represents the end of the abutting T-rail; 3—3 represent the cut-out portions of the outer ends of the rail heads; 4—4 are the concaved or curved limits of said cut-out portions; 5 represents the usual space between the meeting ends of the rails, which is greater or less, dependent upon temperature and other conditions. The head of the rail is represented as 6, the web as 7, the base flanges as 8, the inclined under surfaces of the rail head are 9, the inclined upper surface of the base flanges of the rail are 10, 9 and 10 forming the fishing angles; the holes in the rail webs are indicated at 11, which holes are of slightly larger diameter than the bolts which fit within the same, in order to allow for expansion and 80 contraction of the track.

85

12 represents my outside splice bar in general; 13 is the inside splice bar shown as an angle splice bar; 14 is the upper flange of the outer splice bar showing one form in 95 which it is rolled, as particularly shown in Figs. 3 and 5. I may, however, first roll the bar of section different from that shown in Fig. 3, and then form it into the finished shape by forging, upsetting, swaging and 100 like operations.

95

15 is an upper inwardly projecting rib of the splice bar adapted to contact with the lower inclined surface of the rail head and thereby support it; 16 is the web portion of 105 my outer splice bar; 17 is an inwardly projecting lower rib adapted to contact with the inner part of the base flange of the rail, this portion 17 thus acting in conjunction with the rib 15 to wedge the splice bar in 110 the fishing angle of the rail and form a tight and efficient joint.

105

18 is the lower inclined flanged portion of my outer splice bar; and 19 is the inclined lower surface of the same adapted to 115 fit on and contact with the upper surface of the base flange of the rail.

115

The central or head portion of my improved splice bar is represented as 21 and as particularly shown in Figs. 1, 2 and 4, 120 this portion 21 is of a cross section, substantially similar to the outer portion of the rail head and when fitted in the cuts 3 and 4 of the said rail head, it practically restores the same to its original section.

125

In order to form my bar it may be first rolled of the cross section shown in Fig. 5, with parallel sides, and after it is cut into lengths, the portions 20 are sheared therefrom on the curved lines indicated in Figs. 130

130

6 and 7 in order to produce the finished form of the bar shown in Figs. 1, 8, 9 and others. After this is done, the bar is forged or pressed in suitable dies, or otherwise, into its finished shape. I may, however, make it in other manners, as previously mentioned.

The central inner face of the head portion of my outer splice bar is indicated at 22, and the flanged portions of the said bar which connect therewith and merge into the other portions, as shown, are indicated at 23. The form of this portion 23 is made on a gradual curve so that the bar at no place has abrupt notches or changes of section, which conduces to its strength, elasticity and durability. As the flange 14 is cut away from the end portions of the bar and formed into the shapes shown as 23, the slope of this curved portion 23 is such that no part 20 of it can come in contact with any part of a wheel tread, even though a wheel should be worn to the limit, as indicated in Fig. 10. In order to allow room for tightening my outer splice bar and drawing it firmly 25 into place, either at its first application, or afterward, to allow for the wear of the fishing surfaces and for contraction and expansion, I provide a slight distance or clearance between the upper portion of my outer splice bar and the head portions of the rails, as indicated at 24. The portions of the upper flange of my outer splice bar which project outwardly to the greatest extent are indicated at 25, but these are so arranged and located that they will not, under any conditions, touch a wheel tread which passes over them, even though said wheel tread is badly worn as indicated in Fig. 10. The upper surface of the portion of my outer splice bar which fits under the rail head, is indicated at 26, while 27 are holes in the webs of the splice bars, in which are inserted the bolts 28, provided with the nuts 29 and the spring washers 30.

45 As shown in Fig. 10, the dotted line 31 indicates the outline of a car wheel which has been worn to the permissible limit of wear, according to accepted standards, and it will be seen that the outer and downwardly projecting portions 32 of said car wheel can in no manner touch the flange portions of my outer splice bar, and the portion of my joint presented to the car wheels is of about the same section as that of the body 50 or unbroken portion of the rail, and this constitutes a valuable and important feature of my invention.

33 represents a curved form of my outer splice bar as viewed in plan and 34 is a substantially straight line to which said curved form of the splice bar may be drawn by means of the splice bolts, in order to tighten it very securely when first applied, or to enable it to be tightened thereafter to provide for wear as hereinbefore mentioned.

I am aware that splice bars have been proposed with an outer head portion, either straight, or with inclined ends, or with raised portions at the rail joint, on which the outer part of a car or other wheel is intended to rest in order to carry the wheel over the joint in the rails, the idea of these constructions being to prevent jar. As, however, almost all car wheels are more or less worn, it follows that when the wheels are traversing the body of the rail, they ride generally on their hollow portions and the downwardly projecting outer part of the tread extends beyond the rail. When wheels of this kind, which form practically all of the car wheels used, come to a rail joint of the kinds just described, they will contact forcibly with the outer upper portion of the said joint bar, which forms, so to speak, an outer rail tread, with the result of producing a violent shock at each joint, and instead of serving the purpose intended, of making a smooth bridge, such prior joints have precisely the opposite effect, viz:—to produce a violent shock, and in the case of 85 joints with portions projecting above the rail tread, this shock occurs even with new, unworn wheels. These difficulties are entirely obviated by means of my improved construction, due to the fact that the head 90 portion of my outer splice bar and the adjoining uncut parts of the rail head are the substantial equivalents, in effect, of the original rail head. The joint formed by my construction has, therefore, practically the 95 same effect, as respects the car wheel, as the body of the rail itself, and at the same time provides a smooth bridge and passage for the wheels over the joint, besides holding the rails properly in alinement.

I do not limit myself to a splice bar, the upper portion of which conforms exactly to, or only restores the cut away parts of the rail head, but I may make said upper portion of slightly greater width with outer 100 side surfaces parallel to the rail axis, or with the central portion thereof wider and the ends of the said side surfaces tapering, if desired, to meet the corresponding outer 105 surfaces of the rail heads. In fact said upper portion of my splice bar may be of any widths or form from that of the cut away parts of the rail to a greater width, preferably, however, not greater in width than the groove or depression of a worn car 110 wheel. The general shape of the groove in a car wheel worn to the usual limit is illustrated in Fig. 10, and according to my invention, any outer splice bar the upper portion of which will not interfere with the 115 passage of such a wheel, is within the scope of my claims.

Although I have shown my improved splice bar with only the intermediate portion thereof projecting upwardly and form- 120

ing part of the rail tread and conforming to the original section thereof, I may also make the entire length of my outer splice bar of this construction and make the cuts 5 in the rail heads of corresponding length, as will be readily understood.

Although I have shown and described my construction in considerable detail, I do not wish to be limited to the exact and specific 10 details shown and described, but may use such substitutions, modifications or equivalents thereof, as are embraced within the scope of my invention or as pointed out in the claims.

15 Having thus described my invention, what I claim and desire to secure by Letters Patent is:

1. In a rail joint, a pair of abutting rails the outer sides of the adjoining ends of the 20 heads of which are cut away, an outer splice bar the upper portion of which is fitted therein and substantially conforms to the cut away portions of the original sections of said rail heads, the said upper portion tapering gradually from its ends to the end 25 portions of the splice bar.

2. In a rail joint, a pair of abutting rails the outer sides of the heads of the adjoining 30 ends of which are cut away, an outer splice bar the end portions of which are fitted in the outer fishing angles of said rails, the intermediate portion of which bar fits into said cut away portions of said rail heads and substantially conforms to the original or uncut 35 sections thereof, said intermediate portion tapering gradually to the said end portion.

3. In a rail joint, a pair of abutting rails the outer sides of the adjoining ends of which are cut away, an outer splice bar the 40 intermediate portion of which is mounted in said cuts and tapers gradually therefrom to the ends of the bar, the wheel contact surfaces formed by said joint being not substantially less than that of the uncut rail 45 heads, nor substantially wider than the groove in a limit worn car wheel.

4. In a rail joint, a pair of abutting rails the outer sides of the heads of the adjoining 50 ends of which are cut away, the ends of said cuts merging gradually into the outer lateral surfaces of the rail heads, an outer splice bar the upper portion of which is mounted within said cuts sloping gradually therefrom to the ends of the bar, the upper or tread surface 55 formed thereby conforming substantially in surface to that of the original rail, the width of the tread at said joint being not substantially less than that of the original uncut rail, nor substantially greater than the 60 groove in a limit worn car wheel.

5. A rail joint comprising a pair of abutting alined rails, the outer parts of the adjoining ends of the rail heads being cut away, each of said cuts merging gradually 65 from the rail ends to the outer lateral sur-

face of the rail head, an outer splice bar, the upper portion of which fits within said cut away portions and substantially conforms to the original section of the same and slopes gradually therefrom to the ends of the bar. 70

6. In a rail joint, a pair of abutting rails, the outer sides of the adjoining ends of the heads of which are cut away, each of said cuts merging gradually thence by a curve to the outer lateral surface of the rail head, an 75 outer splice bar the end portions of which are fitted within the fishing angles of said rails, the intermediate portion of which fits into said cut away portions of said rail heads and substantially conforms to the original sections thereof, said intermediate portion tapering gradually and merging into 80 said end portions.

7. A rail joint comprising a pair of abutting rails the outer sides of the adjacent ends 85 of the heads of which are cut away, an outer splice bar, the upper portion of which is fitted within said cuts and tapers gradually therefrom and merges into the end portions of said bar, an inner splice bar of angle form 90 fitting within the fishing angle of said rails, and means for securing said splice bars in position.

8. A rail joint comprising a pair of abutting rails, the outer parts of the adjoining 95 ends of the rail heads being cut away, each of said cuts extending parallel to the rail axis and thence merging gradually to the outer lateral surface of the rail head, an outer splice bar the upper portion of which fits within said cut away portions and substantially conforms to the original section of the same, and tapers gradually thence to the 100 end portions, said end portions of said outer splice bar being adapted to fit within the outer fishing angles of the rail, an inner splice bar fitted within the inner fishing angles and adapted to coöperate with the outer splice bar and the rails aforesaid, and means for securing and adjusting the same 105 in position.

9. In a rail joint, a pair of abutting rails the outer sides of the adjacent ends of the heads of which are cut away, an outer splice bar the upper portion of which fits within 110 said cuts, and a slight distance or clearance between the entire inner side of the said upper portion and the adjoining surfaces of the cuts in said rails, whereby clearance is provided for adjustment and to allow for 115 contraction and expansion.

10. A rail joint comprising a pair of abutting alined rails, each of the ends of the outer parts of the adjacent rail heads being cut away to the rail webs for a short distance, each cut merging thence gradually into the outer lateral surface of the rail head, an outer splice bar the upper intermediate portion of which is fitted in said cuts and 120 conforms to the original section of the said 13

- cut away portions, the end portions of said outer splice bar being fitted within the outer fishing angles of the rail, the intermediate portion extending in a curve and taper to 5 and merging into the said end portions, an inner angle splice bar fitted within the inner fishing angle of said rails, and means for securing and adjusting said splice bars in position.
- 10 11. A rail joint comprising a pair of abutting alined rails, the outer ends of each rail head being cut away in semisegmental form providing together, a space of approximately segmental shape as viewed in plan, 15 an outer splice bar having an upper intermediate portion fitted within said space and conforming to the original sections of the
- cut away portions of the rail heads, the end portions of said outer splice bar being fitted between the rail head and the rail base 20 flange, the intermediate portion extending in a curve and gradual taper to said end portions, an inner splice bar fitted between the head and base flange on the inner side of said rails, bolts passing through said splice 25 bars and rails and provided with nuts for securing and adjusting the said joint.
- In testimony whereof, I hereto affix my signature in the presence of two witnesses.

EDWIN E. SLICK.
